UNITED STATES PATENT OFFICE.

CHARLES F. PEEL, OF NEW YORK, N. Y.

PORTABLE TRACK TRIP DEVICE.

1,153,568.

Specification of Letters Patent. Patented Sept. 14, 1915.

Application filed July 16, 1913. Serial No. 779,319.

To all whom it may concern:

Be it known that I, CHARLES F. PEEL, a citizen of the United States, residing at New York, in the county of Bronx and State 5 of New York, have invented a certain new and useful Improvement in Portable Track Trip Devices, of which improvement the following is a specification.

This invention relates to safety devices 10 adapted to be employed in connection with railways having an automatic stop system or trip members carried by the train for automatically controlling the same, as a trip valve lever adapted to vent the brake pipe 15 and apply the air brakes when the valve is actuated by engagement with the trip device located along the track, the object being to provide an improved portable track trip device which may be carried by a brakeman, 20 flagman, or other employee, and readily applied to the rail at any desired time and place where it is desired to flag or stop a train.

My improvement comprises a simple, 25 light, and durable construction having a body portion designed to conform to a portion of the contour of the rail and to closely engage the same so as to hold the device rigid and prevent any yielding movement 30 of the same when struck by the trip member carried by the train. A preferred construction is formed to engage between the under side of the head and the top of the flange of the rail, said body portion having means 35 for readily clamping same in the desired position, and a projecting arm adapted to actuate the trip member carried by the train.

In the accompanying drawings: Figure 1 is a transverse section of a rail showing one 40 form of my improvement, in which the body portion is designed to closely engage the under side of the head and the top of the flange of the rail; Fig. 2, a similar view showing a modified form of body engaging 45 the top and bottom surfaces of the flange of the rail; Fig. 3, a similar view showing a different form of clamping means for rigidly holding the body portion in position; and Fig. 4, a side view of the form shown 50 in Fig. 1.

According to the construction shown in Figs. 1 and 4, the body portion or block, 4, is designed in outline to conform to the outer surface or contour of the rail, 5, and 55 engages closely between the under side of the head of the rail and the top surface of

the flange. Any suitable or preferred means may be employed for clamping the body portion to the rail, as for instance, a thin flat spring, 6, extending from said body portion under the bottom flange of the rail, and having a hooked end, 7, engaging tightly over the other edge of said flange. A projecting arm, 8, is also provided extending into the path of, and adapted to actuate, 65 a trip member carried by the train, this arm being supported in any convenient manner on the body portion, 4. As shown in Fig. 1, this arm is mounted on a pin or bolt, 9, secured in the body, and may have a lateral 70 adjustment thereon, if desired, or if preferred, all of said parts may be formed integral.

The body portion or block is preferably formed of metal, and of a suitable length, 75 say about two or three inches, to give the desired bearing surface in contact with the rail, and when thus clamped in position, it will be seen that the same is held absolutely rigid against any yielding or turning movement relative to the rail.

According to the modification shown in Fig. 2, the body or block, 4^a, is formed to embrace the upper and lower surfaces of the bottom flange of the rail, 5, and is 85 clamped in position by means of a flat spring, 6, with hooked end, 7, the same as in Fig. 1.

As shown in Fig. 3, the clamping device is fastened to the rail by means of an opening 90 through the web, and such a device may be used where it is not convenient to pass the clamp beneath the bottom flange. In this construction the body or block, 4^b, is formed to engage between the head and the flange 95 of the rail, the same as in Fig. 1, but it is provided with a stem, 11, extending through said block and through an opening, 10, in the web of the rail, the stem having a notch, 15, adapted to fit over the web, and carrying a key, 12, mounted to slide upon said stem and extending through said opening so as to wedge the notched end of the stem upon the web of the rail and thereby rigidly 100 clamp the block in position. The key engages the stem by means of a lug, 13, sliding in the groove or slot, 14, which retains the key on the stem when the same is withdrawn from the opening in the web of the rail. The stem, 11, is rigidly fastened to 110 the block, 4^b, in any suitable manner, and also carries the rigid tripping arm, 8. With

this construction the device may be readily attached to the rail by inserting the stem through the hole, 10, in the web, and then pushing in the key, 12, which wedges the 5 notched end of the stem down upon the web. To detach the same, the key is withdrawn, thereby permitting the stem to be tilted up sufficiently to clear the notch and be removed from the opening.

- 10 From the foregoing description, it will be seen that I have provided a simple and inexpensive construction of a portable trip device, which is light and durable, and may be readily attached to the rail at any point 15 where it is desired to flag or stop a train.

Having now described my invention, what I claim as new and desire to secure by Letters Patent is:

1. A portable track trip device comprising 20 a body portion having a longitudinal surface formed to engage the under side of the head of the rail and closely engage therewith, a clamp extending around to the other side of the rail for holding said body in position, and a projecting arm for operating a trip member carried by the train.
2. A portable track trip device comprising a body portion having a longitudinal surface formed to closely engage a correspond-

ing portion of the surface at one side of the 30 rail, a spring clamp rigidly attached to said body and extending around to the other side of the rail for holding the body in position, and a projecting arm for operating a trip member carried by the train. 35

3. A portable track trip device comprising a body portion having longitudinal surfaces formed to engage the under side of the head and the top of the flange of the rail, a clamp adapted to extend beneath the 40 rail for holding said body in position, and a projecting arm extending into the path of a trip member carried on the train.

4. A portable track trip device comprising a body or block having a longitudinal surface formed to engage the top of the flange of the rail, a spring clamp extending under the bottom of the rail and having a hooked end engaging the edge of the flange, and a projecting arm adapted to actuate a trip 50 member carried by the train.

In testimony whereof I have hereunto set my hand.

CHARLES F. PEEL.
